(Cl. D83—1)

To all whom it may concern:

Be it known that I, Percy R. Finch, a citizen of the United States, residing at Chicago, in the county of Cook and State of Illinois, have invented a new, original, and ornamental Design for a Nursing Bottle Adapter Cap, of which the following is a specification, reference being had to the accompanying drawing, forming a part thereof.

Fig. 1 is a side elevational view of a nursing bottle adapter cap embodying my new design;

Fig. 2 is a side elevational view looking from the right of Fig. 1;

Fig. 3 is a top plan view; and

Fig. 4 is a side elevational view looking from the left of Fig. 1.

I claim:

The ornamental design for a nursing bottle adapter cap, as shown.

PERCY R. FINCH.
